UNITED STATES PATENT OFFICE.

PAUL COTTRINGER AND WILLIAM R. COLLINGS, OF MIDLAND, MICHIGAN, ASSIGNEES
TO THE DOW CHEMICAL COMPANY, OF MIDLAND, MICHIGAN, A CORPORATION OF
MICHIGAN.

METHOD OF MAKING ANHYDROUS MAGNESIUM CHLORIDES.

Application filed March 10, 1921. Serial No. 451,199.

To all whom it may concern:

Be it known that we, PAUL COTTRINGER and WILLIAM R. COLLINGS, citizens of the United States, and residents of Midland, ⁵ county of Midland, State of Michigan, have jointly invented a new and useful Improvement in Methods of Making Anhydrous Magnesium Chlorides, of which the following is a specification, the principle of the ¹⁰ invention being herein explained, and the best mode in which we have contemplated applying that principle so as to distinguish it from other inventions.

The published methods for the production of anhydrous magnesium chloride ($MgCl_2$), up to a very recent date at least, will be found very well summarized in Gmelin-Kraut's "Handbuch der anorganischen Chemie" (1909) II 2, p. 420. In the ²⁰ same connection, the well known difficulties encountered in the production of the water-free salt are recited, the principal such difficulty being that the normal hexa-hydrate will melt and form a solution in its water of crystallization at a relatively low temperature, and dehydration of the resultant solution must be carried on at a very slight increase in temperature and with extreme caution if decomposition of the salt is to be ²⁵ avoided. The present improved method for the production of the anhydrous salt has as its object the avoidance of this particular difficulty, and also provides for the more ready and convenient handling of the material during the preliminary stages of dehydration; as well as for the economical use of hydrochloric acid gas which is used to drive off the last remaining water of crystallization.

⁴⁰ To the accomplishment of the foregoing and related ends the invention then consists of the steps hereinafter fully described and particularly pointed out in the claims, the annexed drawing and the following description setting forth in detail one mode of carrying out the invention, such disclosed mode constituting, however, but one of various ways in which the principle of the invention may be used.

⁵⁰ In said annexed drawing:—

Fig. 1 is a more or less diagrammatic view of an improved apparatus suitable for carrying out the partial dehydration of the ma-

terial in question, and Fig. 2 is a similar view of an apparatus specially designed for ⁵⁵ carrying out the final stage of dehydration, in which a current of hydrochloric acid gas is employed, as indicated above.

The apparatus as shown in Fig. 1 comprises as its principal element a shelf dryer ⁶⁰ 1, through which the material is passed successively from the upper to the lower shelves 2 in well understood manner by means of shovels or plows 3 carried on a rotating shaft 4. The material to be treated is ⁶⁵ fed into the upper end of the dryer by means of a suitable hopper 5 and is discharged at the lower end through an outlet 6. Likewise connected with such lower end of the dryer is a duct 7 through which flue ⁷⁰ gases or products of combustion directly received from a gas or oil burner or from a furnace burning coal or other solid fuel are admitted to the interior of the dryer, through which they circulate in a general ⁷⁵ upward direction, finally escaping through an exit duct 8. Connected with said duct 7 is a valve controlled branch duct or opening 9, whereby outside air may be admitted in a regulated amount and mixed with the aforesaid flue gases so as to lower the temperature of the latter when admitted to the dryer. The dimensions of the apparatus and the temperature and rate of supply of the flue ⁸⁰ gases thus tempered with outside air is regulated so that the highest temperature encountered by the material at the lower or exit end of the dryer will not rise above 350 degrees centigrade, while at the upper end such temperature will not rise above 115 de- ⁸⁵ grees centigrade.

The material as supplied to such upper end of the dryer through feed hopper 5 consists of a mixture of the normal hexa-hydrate and a quantity of the partially dehydrated product as discharged through duct ⁹⁵ 6, the transfer of such portion of the partially dehydrated product being indicated by a line 10 with direction arrow only. Where the highest temperature encountered by the material is 350 degrees centigrade, as just stated, such partially dehydrated product will consist mainly of dihydrate ($MgCl_2 \cdot 2H_2O$), which has a fusion point ¹⁰⁰ above 360 degrees centigrade, and the amount of this product diverted for use in

mixing with the normal hexa-hydrate will be approximately one half of the latter. Where such partially dehydrated product is mixed in amount approximately as stated, 5 with the normal hydrate, the mixture may be immediately subjected to a temperature of approximately 115 degrees indicated above as the temperature of the heating gases as discharged from the apparatus, 10 without any of the harmful effects that would result were the normal hydrate by itself subjected to such temperature.

It will be noted that the foregoing procedure is distinguished from that disclosed 15 in German Patent No. 51,084, dated March 16, 1889. In the first place, in our improved process, it is not the completely dehydrated chloride that is thus admixed with the normal hydrate, and in the second place, in our 20 process, such admixture is simply made with both materials in solid form, without, in other words, fusing the normal hydrate, and then stirring in the dihydrate which results in the production of a hard cake that 25 requires to be broken up before it can be passed through the drying apparatus. The anhydrous product is too valuable to warrant its use in any large commercial way for thus admixing with the normal hydrate and it 30 apparently was never realized that the partially dehydrated product might prove effective in the same manner to render the normal salt amenable to ordinary methods of 35 drying.

35 The portion of partially dehydrated salt, (most if not all in the form of the dihydrate) that is delivered from the shelf dryer in excess of that returned in the fashion just described to be passed through a second time, 40 is thereupon transferred either continuously or intermittently to an externally heated rotary drum dryer 12 for treatment in what may be regarded as a second stage of the process. A current of hydrochloric acid gas 45 is continuously passed through said dryer 12 as it rotates, such gas being derived initially from any suitable source. The circuit of the gas includes one or more towers through 50 which sulphuric acid of proper strength is passed, either in the same direction or counter to the current of hydrochloric acid gas, so as to remove therefrom substantially all 55 traces of water. In the illustrative form of apparatus shown in Fig. 2, two such towers 13 are thus included in the circuit 14, through which the hydrochloric acid gas is 60 caused to flow by means of a pump 15, suitable valves being provided whereby such flow of gas can be diverted from one to the other tower 13 as desired. A sufficient body of sulphuric acid is kept circulating through the particular tower that happens to be thus in use and such circulation continued until the sulphuric acid reaches a density of approximately 60 degrees Baumé, whereupon

the hydrochloric acid gas is switched to the other tower where another portion of sulphuric acid of proper strength to remove the water from the gas is ready to be circulated. A concentrator 16 is connected with the 70 pipes 17 whereby the circulation of sulphuric acid is thus maintained in the respective towers 13, so that such acid after absorbing the maximum amount of water that a desirable may be concentrated and the acid 75 then returned for use over again, as will be readily understood.

The circulation of the hydrochloric acid gas may thus be continued as long as found necessary to effect the dehydration of 80 any particular batch of partially dehydrated magnesium chloride in drum 12, or by providing suitable means for continuously feeding such chloride to and removing same from said drum, the circulation of the hydrochloric acid gas may be continued indefinitely. Where the chloride is dried in batches the temperature in said rotary drum 12 will be gradually raised from approximately 200 degrees to approximately 500 90 degrees centigrade, the higher temperature being necessary to insure the complete driving off of the water of crystallization; while if continuous operation is to be secured the partially dehydrated chloride 95 is introduced at one end of the drum, which end is maintained at the lower temperature just indicated, and such temperature gradually increased lengthwise of the drum until at its other, discharge end the 100 higher temperature is reached.

By means of the foregoing steps and apparatus it is possible to prepare anhydrous magnesium chloride at a much lower cost than has heretofore been possible, the bulk 105 of the water of crystallization being driven off by ordinary air drying and only the last stage requiring the use of hydrochloric acid gas. The latter moreover is used over and over again without material loss save such as 110 may occur due to leakage and the like. It will be understood, of course, that the process is not limited to any precise degree of dehydration being reached at the end of the first stage, since hydrochloric acid gas will 115 be effective to remove water of crystallization in excess of two molecules, but the drying in the first stage is preferably carried to as near this point of dehydration as possible for reasons of economy. If the process be 120 carried out with the temperature ranges as hereinbefore described, the product resulting from the first stage will be substantially all in the dihydrate form.

Other modes of applying the principle 125 of our invention may be employed instead of the one explained, change being made as regards the steps herein disclosed, provided those stated by any of the following claims 130 or their equivalents be employed.

We claim:

1. In a method of making anhydrous magnesium chloride, the steps which consist in intermixing partially dehydrated magnesium chloride with the normal hydrated salt, both in solid form, and then directly heating the mixture at a temperature sufficiently elevated to drive off water of crystallization.
- 10 2. In a method of making anhydrous magnesium chloride, the steps which consist in intermixing a quantity of the dihydrate salt with the normal hydrated salt, both in solid form, and then directly heating the mixture at a temperature sufficiently elevated to drive off water of crystallization.
- 15 3. In a method of making anhydrous magnesium chloride, the steps which consist in intermixing partially dehydrated magnesium chloride with the normal hydrated salt, both in solid form, and then directly heating the mixture through a temperature range gradually increasing from approximately 115 to approximately 350 degrees centigrade.
- 20 4. In a method of making anhydrous magnesium chloride, the steps which consist in intermixing a quantity of the dihydrate salt with the normal hydrated salt, both in solid form, and then directly heating the mixture through a temperature range gradually increasing from approximately 115 to approximately 350 degrees centigrade.
- 25 5. In a method of making anhydrous magnesium chloride, the steps which consist in intermixing a quantity of the dihydrate salt with the normal hydrated salt,
- 30 driving off water of crystallization from the resulting mixture until it reaches approximately the dihydrate stage, and returning a portion of the product for use over again in the preceding steps.
- 35 6. In a method of making anhydrous magnesium chloride, the steps which consist in driving off a portion of the water of crystallization from the normal hydrated salt by a current of gases of combustion, and regulating the temperature of such gases by admixing air at normal temperature therewith.
- 40 7. In a method of making anhydrous magnesium chloride, the steps which consist in driving off a portion of the water of crystallization from the normal hydrated salt by moving the latter in opposed direction against a current of gases of combustion, and regulating the temperature of such gases by admixing air at normal temperature therewith.
- 45 8. In a method of making anhydrous magnesium chloride the steps which consist in driving off a portion of the water of crystallization from the normal hydrated salt by moving the latter in opposed direction against a current of gases of combustion, regulating the temperature of such gases by admixing air at normal temperature therewith, and returning a portion of the product for use over again in the preceding steps.

Signed at Midland, Mich., this 4th day of March, 1921.

PAUL COTTRINGER.
WILLIAM R. COLLINGS.
